ABSTRACT OF THE DISCLOSURE

A heat-conductive drum textile heater has an inlet portion which is smooth and cylindrical, a smooth descending conical portion toward a takeoff end, and a downward step either at one or the other end of the smooth conical portion. The drum is adapted to receive two ends of synthetic thermoplastic continuous filament yarn twisted into plies, to heat and shrink them, and to discharge to mechanism which separates the ends into bulked yarn having stretch characteristics. The drum may be used with a rotating downwardly tapering pin about which the yarn is wrapped.

DESCRIPTION OF INVENTION

The present invention relates to textile machinery for producing bulked synthetic thermoplastic continuous filament yarn.

A purpose of the invention is to ply two ends of synthetic thermoplastic continuous filament yarn twisted with respect to one another, to bring the plied yarn against the outside of a rotatable drum heater at an inlet end having a smooth cylindrical portion and carry the yarn in one or more loops around the cylindrical portion, to carry the yarn in one or more loops around a descending smooth conical portion to a takeoff end, the yarn being heated while on the drum to its thermoplastic temperature, to drop the yarn over a step at one or the other end of the smooth conical portion, and then to cool the yarn to set it and separate it into bulked yarn ends.

A further purpose is to compensate for backup of twist from the separating means toward the means for plying the yarn and allow for shrinkage by adjustment of the position of loops of yarn on the drum.

A further purpose is to guard against the danger of breakage of a plied end on a drum heater by allowing for compensation of change in dimension caused by shrinkage or backup of twist.

A further purpose is to provide a heater drum which has sequentially encountered by the yarn a smooth cylindrical portion, an abrupt descending step, and a descending smooth tapering portion.

A further purpose is to provide a heater drum which has sequentially encountered by the yarn a smooth cylindrical portion, a smooth descending conical portion, an abrupt descending step and then a takeoff portion which may desirably be smooth and cylindrical.

A further purpose is to associate a heater drum having sequentially encountered by the yarn a smooth cylindrical portion and a descending smooth conical portion with a rotating pin around which the yarn passes which has a smooth cylindrical portion opposite the smooth cylindrical portion on the drum and which has a descending conical portion opposite the descending conical portion on the drum.

A further purpose is to wrap the yarn in a plurality of loops around the heater drum and around a post or around

2

a plurality of posts, the post or posts or one of the posts being either a fixed nonrotatable post or a post rotating around its own axis.

Further purposes appear in the specification and in the claims.

5 FIG. 1 is a diagram showing the complete textile operation of plying of two yarn ends twisted together, heating on the drum heater, cooling to set the bulk effect, and then deploying or separating the yarn ends and forming packages.

10 FIG. 2 is a side elevation of a preferred drum heater of the invention partially broken away to show one set of bearings.

15 FIG. 3 is a front elevation of the drum heater of FIG. 2.

15 FIG. 4 is an enlarged fragmentary axial section of the drum heater of the invention.

20 FIG. 5 is a side elevation similar to FIG. 2 of a modified heater drum of the invention showing also a rotating pin.

25 FIG. 6 is a front end elevation of the device of FIG. 5. In the prior art numerous processes have been developed for creating bulk and yarn stretch characteristics in synthetic thermoplastic continuous filament yarn such as nylon and the like. The problem is rendered difficult by operation at higher and higher linear speeds, speeds of 40 yards per minute being now employed, and higher spindle speeds sometimes as high as 150,000 r.p.m.

30 Usually the creation of bulk and stretch characteristics involves a combination of heating and twisting and then cooling so that the effect of the twist is set. Considerable use has been made of longitudinal or strip heaters, but as linear speeds have increased these have tended to become longer, so that they are no longer convenient. Rotatable drum heaters have been developed, for example according to McCord and Ross U.S. patent application Ser. No. 580,978, filed Sept. 21, 1966, for Rotating Drum Heater for Synthetic Yarn. This device conducts the yarn through channels on the surface of a drum.

35 40 Recently a duo-twist process has been adopted for creating bulk and stretch in thermoplastic continuous filament synthetic yarns, by which two such yarn ends are twisted together to form a plied yarn, the plied yarn is heated to render it thermoplastic and then cooled to

45 set the yarn, and then the bulked yarn ends are separated and formed into packages. See Carruthers U.S. Pat. No. 3,091,908, granted June 4, 1963. This process creates a problem if a prior art drum heater is used. Not only does the yarn undergo shrinkage as in all similar cases, 50 but there is a pronounced tendency, even where adequate allowance is made for shrinkage on the drum heater, for the yarn to break on or adjacent to the drum heater.

55 I have discovered that this breakage is due to the tendency of false twist to back up from the point at which the yarn ends are separated toward the point at which the plies are initially formed. I have discovered that this breakage can be prevented by bringing the plied yarn onto the heater drum on a smooth cylindrical preheating section and then passes the yarn along a descending

60 smooth conical portion. At one or the other end of the smooth conical portion there is an abrupt descending step over which the yarn drops. One or more loops of yarn are wrapped around the cylindrical portion and one or more loops of yarn are wrapped around the conical portion and the yarn loops tend to adjust their positions along the axis of the drum as required to compensate for the backup twist. Thus the yarn tends to stabilize

its position as it passes over the drum without undergoing such excessive loads that breakage occurs.

It is believed that the best application of the invention is likely to be in creating nylon yarn with bulk and stretch characteristics from continuous filament yarn usually having multifilaments. For this purpose the outside temperature of the drum should be approximately 400° F., that is, in the range between 350° and 450° F.

The invention is also applicable to other continuous filament thermoplastic yarns at appropriate temperatures for each of them, for example polyester yarn, polyvinylchloride yarn, polyvinylchloride acetate yarn, cellulose acetate yarn and polypropylene yarn.

The invention is intended to be applied to continuous filament synthetic thermoplastic yarn, examples being 70 denier, 34 filament nylon yarn and 70 denier, 17 filament nylon yarn.

The broad concept of running yarn over a cone with takeoff at the small end is old in Cadden U.S. Pat. No. 2,218,504, granted Oct. 22, 1940, and Stanley U.S. Pat. No. 3,221,385, granted Dec. 7, 1965. Running yarn over a cone with takeoff at the large end is shown by Cotchett U.S. Pat. No. 2,174,688, granted Oct. 3, 1939, and McCrosky U.S. Pat. No. 2,370,180, granted Feb. 27, 1945. None of these devices provides a cylindrical drum heater having a smooth cone descending from the cylinder to a takeoff at the small end with an abrupt step at one or the other end of the smooth conical portion.

In one form of the invention which will first be described, the step is provided at the point where the smooth cylindrical portion joins the descending smooth conical portion. This will be described first after which the description refers to a form in which the abrupt step is at the small end of the smooth conical portion.

FIG. 1 illustrates diagrammatically equipment to which the invention is applicable, this being for example a duo-twist installation for creating bulk and stretch characteristics in thermoplastic yarn such as nylon.

Yarn end 20 is withdrawn from a source 21 and passes through the hollow interior of a stationary bobbin 22 supported at a point 23 near its upper end. Another synthetic thermoplastic yarn end 24 is withdrawn from a source 25 and wrapped in a series of helical turns 26 around the outside of the bobbin and then wrapped around the yarn end 20.

As the yarn end 20 advances, the yarn end 24 advances with it, pulling off lower turns from the bobbin and at the same time more turns of yarn end 24 are formed toward the top of the bobbin, so that at a point 27 each of the yarn ends 20 and 24 is plied together, being helically wound with respect to the other yarn end, all as well known in the art.

The two-ply thermoplastic yarn 28 is brought into tangential contact with the outside of a heater drum 30 according to the present invention at its inlet end 31 and progresses along the drum to the takeoff end 32.

At the inlet end the yarn encounters a smooth outside cylindrical portion 33 which is of short extent since its main function is to preheat the thermoplastic yarn. Then the yarn encounters an abrupt descending step 34 which is placed approximately at the point where extensive shrinkage occurs (nylon undergoes 14% shrinkage in the thermoplastic range). A step dimension of 0.05 inch on a side has been found to be adequate. Then follows a smooth gradual descending conical portion 35 to the takeoff end 32. While various angles may be used on this descending conical portion depending on the extent of backup of twist to be compensated for, I find that the angle of the conical portion should preferably be in the range from about 5° to 25° and most desirably about 15° with respect to the axis of the drum.

Around the conical portion 35 of the drum there will suitably be from three to five or six loops 38 each of which in the preferred embodiment passes around the outside of the post 37 as shown.

A rim 40 at the inlet end prevents the yarn from running off the drum at that end and a rim 41 at the takeoff end prevents the possibility that the yarn will run off the drum at the other end.

In many installations the drum heater will provide all the heat that is necessary, but in FIG. 1 I show an optional supplemental longitudinal or strip heater 42 having a heating chamber 43 through which the plied yarn passes.

From the heater or the last heater the plied yarn is guided over canted rolls 44 and 45 so that it cools, while twisted, below the thermoplastic range and is set in a stretch 46. The plied ends are then taken apart or separated into bulked ends 47 and 48 having stretch characteristics and these separate ends are run through guides 50 and 51 to form packages in containers 52 and 53 as well known.

Thus the thermoplastic yarn ends 20 and 24 are first plied together and helically wound about one another and then heat set and then deployed to form bulked and stretch-capable yarn ends 47 and 48.

As the heater drum operates in FIG. 1, the tension on the individual turn may vary and rather than breaking the loops, readjustment can take place by slipping of loops along the conical portion or failing to slip along the conical portion and by pulling of loops from the cylindrical portion of the drum over the step. This effect varies with the extent to which twist backs up onto the conical portion of the drum as a result of the twist introduced and the deploying action which separates the bulked ends. An equilibrium condition is reached between the tendency of the twist to back up onto the cone and the tendency of the loops to slip along the cone and thus the machine operates effectively at high speeds without serious breakage.

The drum 30 as best seen in FIGS. 2 to 4 has a hollow interior 54 so that it can surround a heater. A suitably hollow shaft 55 is journaled on antifriction bearings 56 mounted in a housing 57 which has a tubular bearing portion 58 and at the outer end is provided with a flange 60. The shaft has an opening 59 which permits air to circulate to cool the bearings. At one end of the shaft 55 there is provided a suitably conical portion 61 which seats in a central conical opening 62 on the drum and is held in place by a screw 63 threaded into the end of the shaft.

Depending on the installation, the drum may idle under the forward motion imparted by the takeup mechanism to the yarn by means not shown, or the shaft may be driven, suitably by a drive which has limited torque capability such as a shaded pole electric motor so that the drum speed will respond to variations in tendency of the yarn to move forward.

Within the hollow of the drum there is placed a heater, and while the heater can be a steam, hot air, or other suitable heater as desired, it is preferable to use an electric resistance heater. A suitable ceramic insulator 64 has a hollow central opening 65 large enough to receive the shaft 55 with proper clearance, a shank portion 66 extending forward within the hollow of the drum 30, and a flange portion 67 which extends outward against the flange 60 of the housing and is anchored with the housing by screws 68 extending into a mounting 70.

Around the ceramic shank 66 is mounted an electric resistance heater 72 which is stationary within the drum 30 and is connected to a suitable source of electric power as by leads 73.

At one position around the circumference adjacent the outside of the drum 30 a guide post 37 is mounted by a screw 71 into the mounting 70. The guide post 37 may be wholly stationary or it may have a rotatable spool on the outside but in any case the post 37 has a fixed axis 75 and does not revolve around the drum. The post may

have a guide groove 69 opposite the inlet point, but otherwise it is smooth to permit loops to slide axially.

In the form of the invention shown in FIGS. 5 and 6 the large end of the smooth descending conical portion 35 adjoins the smooth cylindrical portion 33 and an abrupt descending step 34' is provided between the small end of the smooth conical portion 35 and a desirably smooth and cylindrical takeoff portion 70 adjoining the rim 41 at the small end. Thus, as shown in FIG. 5, the yarn 28 entering the heater drum passes around the smooth cylindrical portion with at least a single turn, and then has multiple turns, for example two or three, around the descending conical portion before leaving the drum.

The yarn passes around the post 37 as previously described on each of its turns but in the form of FIGS. 5 and 6 each of the turns optionally also passes around a rotating pin 71 which is rotatably mounted on a center shaft 72 by bearings not shown. The shaft 72 is supported on the base. The rotating pin 71 has a flange 73 at the inlet end and then a smooth cylindrical portion 74 equal in length to the smooth cylindrical portion 33 on the drum. Then there is a smooth descending conical portion 75 which is at least as long as the smooth descending conical portion 35 on the drum, and which desirably continues to the takeoff flange 76.

The tapered portion of the rotating pin has a percentage reduction in diameter from the large end to the small end which is the same as the percentage reduction in diameter of the conical portion of the drum. This feature permits the yarn to drive both the drum and the rotating pin (assuming that they are driven by the yarn) without skidding circumferentially either on the rotating pin or on the drum.

While the process and device of the invention may employ wrapping of each loop around the drum and around a single post, it may also wrap each loop around the drum and around two or more posts. The post or one of the posts may be a nonrotatable post as in the form of FIGS. 1 to 4. The posts or one of the posts may be a rotatable or roller type post as shown in FIGS. 5 and 6.

In FIGS. 5 and 6 only one post may be used, and this may be either a nonrotatable post or a rotatable post, or a plurality of posts may be employed.

The presence of the step 34' at the outlet end in the form of FIGS. 5 and 6 is favorable in a yarn where the shrinkage occurring on the drum due to heat is more gradual than the shrinkage due to twist. By placing this step 34' at the point where the twist shrinkage is more pronounced, the shock to the yarn from the twist shrinkage is less severe and there is less likelihood of breakage.

The drum is made of a heat conducting metal, preferably aluminum alloy. It is preferable however to use a coating on the outside to guard against staining the yarn and this may be a cermet coating which is preferably of grey-black color so as to increase the emissivity from the standpoint of heat transfer.

In operation two ends of thermoplastic continuous filament synthetic yarn are plied together so that each is twisted with respect to the other, and then the plied ends are passed in one or more loops around the cylindrical preheating portion of the heater drum of the invention, passing around a guide post as part of each loop. At the place where the most pronounced shrinkage takes place the plied yarn falls over a step. If heat shrinkage is most severe the form of FIGS. 1 to 4 is preferred and if twist shrinkage is most severe, the form of FIGS. 5 and 6 is preferable. Several loops of yarn are wrapped around the conical portion, each loop at a part of its circumference passing over a guide post and then the yarn is carried through a cooling stretch, after which it is separated or deplied and the individual bulked yarn ends having stretch characteristics are formed into packages.

Optionally there may be supplemental heating after passing through or over the heater drum.

On the heater drum of the invention, an adjustment takes place in relative positions on the loops, brought about by backing up of twist from the point of separation of the bulked yarn ends having stretch characteristics to the heater drum, combined with the shrinkage effect, the adjustment being predominantly on the conical portion toward the takeoff end of the drum.

In view of my invention and disclosure, variations and modifications to meet individual whim or particular need will doubtless become evident to other skilled in the art to obtain all or part of the benefits of my invention without copying the machine shown, and I, therefore, claim all such insofar as they fall within the reasonable spirit and scope of my claims.

Having thus described my invention what I claim as new and desire to secure by Letters Patent is:

1. In textile machinery, means for plying two ends of synthetic thermoplastic continuous filament yarn twisted with respect to one another, a rotatably mounted heater drum having an inlet end and a takeoff end, the drum having a smooth cylindrical portion at the inlet end on which the plied yarn enters in contact with the outside 20 of the drum, a smooth descending conical portion toward the takeoff end from which plied yarn leaves contact with the outside of the drum, a downward step at one end of the smooth conical portion, heater means inside the drum, a guide post beside the drum around which the 25 plied yarn is wrapped for part of each turn, and means beyond the takeoff end of the drum for separating the two yarn ends to produce bulked yarn, the yarn in turns wrapped around the drum compensating for backup of 30 twist from the separating means toward the means for 35 plying the yarn and allowing for shrinkage of yarn.
2. A machine of claim 1, in which the downward step is located at the large end of the conical portion.
3. A machine of claim 1, in which the downward step is located at the small end of the conical portion.
4. A machine of claim 1, in which the post has a groove opposite the cylindrical portion of the drum.
5. A machine of claim 1, in which the post is non-rotatable.
6. A machine of claim 1 in which the post is rotatable.
7. A machine of claim 1, in which the post is rotatable on an axis parallel to the drum axis and around which the yarn is wrapped on each turn, the rotatable post having a smooth cylindrical portion opposite the smooth cylindrical portion on the drum and a descending smooth 45 conical portion opposite the descending smooth conical portion on the drum.
8. A machine of claim 5, in which on the smooth conical portion of the rotating post the percentage of reduction in diameter is the same as on the smooth conical portion on the drum.
9. In a heater for running lengths of yarn, a hollow heat conductive drum having an inlet end and a takeoff end, the drum having at the outside at the inlet end a smooth cylindrical portion, at the outside toward the takeoff end a smooth descending conical portion, an abrupt descending step at the outside at one end of the smooth 50 conical portion, a shaft supporting the drum for rotation, bearings rotatably mounting the shaft, a base supporting the bearings, a heater within the drum and around the shaft, and a guide post beside the drum on the base.
10. A heater of claim 9, in which the abrupt descending step is at the large end of the conical portion.
11. A heater of claim 9, in which the abrupt descending step is at the small end of the conical portion.
12. A heater of claim 9, in which the post is nonrotatable.
13. A heater of claim 9, in which the post has a single groove opposite the cylindrical portion.
14. A heater of claim 9, in which the post is rotatably disposed beside the drum on an axis parallel to the drum 75

axis, having a smooth cylindrical portion opposite to the smooth cylindrical portion on the drum and a smooth descending conical portion opposite the smooth descending conical portion on the drum.

15. A heater of claim 14, in which the conical portion on the rotating post reduces in diameter by the same percentage as the conical portion on the drum.
